UNITED STATES PATENT OFFICE

107,702

DESIGN FOR A KNITTED HOOD AND SCARF ASSEMBLY

Samuel Rosenberg, Milwaukee, Wis.

Application November 22, 1937, Serial No. 73,103

Term of patent 7 years

To all whom it may concern:

Be it known that I, Samuel Rosenberg, a citizen of the United States, residing at Milwaukee, in the county of Milwaukee and State of Wisconsin, have invented a new, original, and ornamental Design for a Knitted Hood and Scarf Assembly, of which the following is a specification, reference being had to the accompanying drawing, forming part thereof.

In the drawing:

I claim:

The ornamental design for a knitted hood and scarf assembly, as shown.

SAMUEL ROSENBERG.
